vale, Pa., a corporation of Pennsylvania

Application August 6, 1938, Serial No. 223,464

9 Claims. (Cl. 246—123)

My invention relates to control apparatus, and is particularly well adapted for, but not limited to, controlling a device which records the presence of vehicles upon a selected stretch of trackway.

An object of my invention is the provision of novel and improved means to control a device for recording the arrival of vehicles at selected points on a stretch of trackway over which vehicles move in both directions whereby the speed of such vehicles may be accurately determined. Other objects and advantages of my invention will appear as the specification progresses.

I shall describe three forms of apparatus embodying my invention, and shall then point out the novel features thereof in claims.

In the accompanying drawings, Fig. 1 is a diagrammatic view showing one form of apparatus embodying my invention when applied to measuring the speed of railway trains. Figs. 2 and 3 are each diagrammatic views showing modified forms of the apparatus shown in Fig. 1 and also embodying my invention.

Similar reference characters refer to similar parts of each of the several views.

Referring to Fig. 1, the reference characters 1 and 1a designate the traffic rails of a stretch of railway track X over which traffic moves in both directions. Located at selected, spaced points along the stretch of track X are actuators M₁ and M₂ so positioned as to be actuated by a train operating along track X. While the distance between the selected points at which the actuators are located may be of any convenient value, the actuators are preferably located a measured distance apart. The actuators M₁ and M₂ are preferably alike, and may be any one of the well-known forms of track instruments, such as, for example, that type covered by United States Letters Patent No. 1,834,077 issued to A. J. Sorensen on December 1, 1931, wherein the resistance is normally low but is increased due to the vibration caused by a passing train; or that type covered by United States Letters Patent No. 2,076,928 issued to H. G. Witmer on April 13, 1937 wherein a normally closed contact is opened due to the passage of a train.

The reference character R₁ designates an operating or stick relay associated with track instrument M₁. Relay R₁ is provided with a slow releasing repeater relay RP₁ which is energized over a simple circuit including front contact 2 of relay R₁. The reference character R₂

designates an operating or stick relay associated with track instrument M₂, and which relay is provided with a slow releasing repeater relay RP₂ energized over a simple circuit including front contact 3 of relay R₂.

The reference character CR₁ designates a control relay governed by relays R₁ and R₂ in response to eastbound traffic; the reference character CR₂ designates a control relay governed by relays R₁ and R₂ in response to westbound traffic; and each relay CR₁ and CR₂ governs a multiple path of a control circuit for an electroresponsive device RD.

The electroresponsive device RD governed by control relay CR₁ or CR₂ may be any desired type of electroresponsive device and in the particular embodiment of my invention selected as an illustration, I shall assume that device RD is any one of the well-known forms of recording devices capable of indicating and recording the length of time that such device is energized. One form that device RD may take is shown in the copending application for Letters Patent, Serial No. 216,248, filed on June 28, 1938, by Bernard E. O'Hagan for Control apparatus. As will be evident from an inspection of Fig. 1, device RD is normally deenergized, and is energized over front contact 10 of relay CR₁ or front contact 16 of relay CR₂.

The reference character SP designates a normally deenergized directional relay which is energized whenever relay R₁ or R₂ is deenergized or whenever relay CR₁ or CR₂ is energized, the circuit for relay SP including four multiple paths, a first of which is completed over back contact 7 of relay R₁, a second of which is completed over back contact 14 of relay R₂, a third of which is completed over front contact 9 of relay CR₁ and a fourth of which is completed over front contact 17 of relay CR₂. Relay SP is preferably provided with slow release and slow pick-up characteristics.

In the normal condition of the apparatus, as shown in Fig. 1, no train is operating upon the selected stretch of railway track X, so that track instruments M₁ and M₂ are unactuated, relays R₁, R₂, RP₁ and RP₂ are energized; and relays SP, CR₁ and CR₂ are deenergized.

Having thus described the various parts of the apparatus of Fig. 1 embodying my invention, I shall explain their operation for an eastbound train, and shall at the same time trace the circuits controlling each part of the apparatus.

When an eastbound train reaches track instrument M₁, the actuation of that instrument 55

interrupts a stick circuit for relay R_1 passing from terminal B of a suitable source of current, such as a battery not shown, through instrument M_1 , the winding of relay R_1 and front contact 5 of relay R_1 to terminal C. Relay R_1 releases, opening front contact 4 to open the stick circuit for relay R_1 previously traced, and opening front contact 2 to open the energizing circuit for relay RP_1 . Relay RP_1 releases at the end of 10 its slow release period to close back contact 12 and thereby prepare a pick-up circuit for relay R_1 , which circuit may be traced from terminal B through instrument M_1 , the winding of relay R_1 , and back contact 12 of relay RP_1 to terminal 15 C. The releasing of relay R_1 also closes back contacts 5 and 7, the closing of back contact 7 of relay R_1 completing the first circuit for relay SP with the result that relay SP is energized and picks up at the end of its slow pick-up period. 20 With relay R_1 released closing back contact 5 and before relay SP is picked up opening its back contact 6, relay CR_1 is energized over a pick-up circuit passing from terminal B through front contact 3 of relay R_2 , winding of relay 25 CR_1 , back contact 6 of relay SP, and back contact 5 of relay R_1 to terminal C. Relay CR_1 on picking up closes its own front contact 8 to thereby complete a stick circuit for that relay which shunts back contacts 5 and 6 of relays R_1 30 and SP, respectively. The closing of front contact 9 of relay CR_1 completes the second circuit for relay SP, and the closing of front contact 10 of relay CR_1 completes one path of the control circuit for device RD so that device RD 35 is energized to start its record.

Recording device RD remains energized until such time as the train reaches track instrument M_2 . The actuation of instrument M_2 interrupts a stick circuit for relay R_2 passing from terminal 40 B through instrument M_2 , the winding of relay R_2 and front contact 13 of relay R_2 to terminal C, with the result that relay R_2 releases; thereby opening front contact 13 to open the previously traced stick circuit for relay R_2 , and opening 45 front contact 3 to open the previously mentioned stick circuit for relay CR_1 . Relay CR_1 releases to open front contacts 8, 9 and 10, the last of which opens the control circuit with the result that device RD becomes deenergized and ceases 50 to record. The closing of back contact 14 of relay R_2 completes the third circuit for relay SP through that contact, and since relay SP is energized, a pick-up circuit for relay CR_2 passing from terminal B through front contact 2 of relay 55 R_1 , winding of relay CR_2 , back contact 11 of relay SP and back contact 15 of relay R_2 to terminal C is open at back contact 11 of relay SP so that relay CR_2 remains deenergized, the control circuit for device RD remaining open at 60 front contact 16 of relay CR_2 . The opening of front contact 3 of relay R_2 also interrupts the energizing circuit for relay RP_2 , and relay RP_2 releases at the end of its low release period to close back contact 19 and prepare a pick-up circuit 65 for relay R_2 passing from terminal B through instrument M_2 , the winding of relay R_2 , and back contact 19 of relay RP_2 to terminal C.

When the train completely passes track instrument M_1 , relay R_1 picks up over its pick-up 70 circuit, and relay RP_1 also picks up. Relay R_1 is now held energized over its stick circuit. When the train completely passes track instrument M_2 , relay R_2 picks up over its pick-up circuit, relay RP_2 also picks up, and relay SP releases. The apparatus is now in its normal condition. 75

It is to be noted that device RD is energized during the interval required for the head end of a train to pass from instrument M_1 to instrument M_2 . It follows that since the distance between instruments M_1 and M_2 is known, and since recorder RD records the interval required for a train to pass from instrument M_1 to instrument M_2 , the speed of a train operating along track X may be accurately computed and determined. 10

The operation of the apparatus of Fig. 1 for a westbound train is similar to that just described for an eastbound train, as will readily be apparent from an inspection of the drawings, and further detailed description is deemed unnecessary, except to point out that relay CR_2 serves as a control relay for governing the control circuit for a westbound train. 15

It should be noted that the slow pick-up characteristics provided for relay SP permit relay CR_1 or CR_2 to be picked up over back contact 6 or 11 of relay SP, prior to directional control being effected when the relay SP picks up. It should further be noted that, when the train is positioned so as to operate the second actuator 25 with the result that the control relay CR_1 or CR_2 is released and no longer completes an energizing circuit for relay SP, the directional control is maintained by virtue of the slow releasing characteristic of relay SP cooperating 30 with the slow releasing characteristics of the repeater relays RP_1 and RP_2 . That is to say, when the train is positioned so that it operates both track instruments, of when the train activates only the second track instrument, the relay 35 SP is controlled only by the stick relays R_1 and R_2 . It can be seen that, for an intermittent actuation of track instrument M_1 or M_2 resulting from the slow passage of a train past the instrument, once relay R_1 or R_2 picks up due to the 40 intermittent actuation to energize its associated repeater relay RP_1 or RP_2 , the pick-up circuit for relay R_1 or R_2 is reestablished only when relay RP_1 or RP_2 releases at the end of its slow release period. It follows that since the relay SP 45 will not release, when deenergized, until it reaches the end of its slow release interval, and since the energizing circuit for relay SP is not opened until relay R_1 or R_2 picks up at the end of the slow release period of its associated repeater relay, the slow release repeater relays and the slow release, slow pick-up relay SP may be adjusted so as to prevent false operation of device RD. 50

Referring now to Fig. 2, the apparatus of Fig. 55 1 is modified by the provision of a track section having a track relay, and by a time element relay TER being added to the apparatus. The track rails 1 and 1a are divided by means of the usual insulated track joints 20 to form a track 60 section, which section preferably includes the locations at which track instruments M_1 and M_2 are located, and which section is provided with a track circuit consisting of a track battery 21 connected across the track rails at one end of 65 the section, and the winding of track relay TR connected across the track rails at the other end. Stick relay R_1 is now provided with a second pick-up circuit passing from terminal B through front contact 22 of relay TR , the winding of relay 70 R_1 and front contact 23 of relay TR to terminal C. Stick relay R_2 is now provided with a second pick-up circuit passing from terminal B through front contact 24 of relay TR , the winding of relay 75 R_2 and front contact 25 of relay TR to terminal 75

C. The control circuit for device RD now passes from terminal B through back contact 26 of relay TR, front contact 10 of relay CR1 or front contact 16 of relay CR2, and device RD to terminal C.

Relay TER is provided with back contacts 29, 30 and 31, which contacts open at the expiration of a predetermined interval after relay TER is energized, this interval preferably being longer in duration than the time required for the head end of a slow moving train to traverse the distance between the locations of instrument M1 and instrument M2. The relay TER is energized in multiple with relay SP, and hence is provided with an energizing circuit having the four branch paths previously mentioned for the circuit of relay SP, the paths for relay TER including its own back contact 29, in addition to the winding of the relay and the control contacts previously mentioned. The stick circuits for relays CR1 and CR2 are each modified to include a back contact of relay TER, the stick circuit for relay CR1 passing from terminal B through front contact 3 of relay R2, the winding of relay CR1, front contact 8 of relay CR1 and back contact 30 of relay TER to terminal C; and the stick circuit for relay CR2 passing from terminal B through front contact 2 of relay R1, the winding of relay CR2, front contact 18 of relay CR2, and back contact 31 of relay TER to terminal C.

The operation of the apparatus of Fig. 2 is similar to the operation of the apparatus of Fig. 1, the track relay TR and time element relay TER being added to the apparatus of Fig. 1 to terminate the operation of device RD in the event that a train actuates track instrument M1 or M2, and then recedes past the track instrument it has actuated, so that the second track instrument is not actuated by the train. This is to say: a train entering the track section shunts relay TR with the result that relay TR releases. The release of relay TR opens the second pick-up circuits for relays R1 and R2, and also closes back contact 26 so that the control circuit for device RD may be completed at front contact 10 of relay CR1 or front contact 16 of relay CR2. For a train which actuates both track instruments M1 and M2, the operation of the apparatus of Fig. 2 is substantially the same as was explained in detail for the apparatus of Fig. 1 except that relay TER is now energized during the interval that relay CR1 or CR2 is picked up. It can be seen, however, that since the pick-up period for relay TER is preferably longer than the interval required for a moving train to actuate instruments M1 and M2, the energization of relay TER, and the picking up of relay TR when the train vacates the track section, does not affect the operation of the apparatus. For a train which actuates track instrument M1 or M2 to start the operation of device RD and then backs out of the track section with the result that the other track instrument is not actuated, the track relay TR picks up when the track section is vacated by the train to complete the second pick-up circuit for relays R1 and R2 and to open back contact 26 with the result that the control circuit for recorder RD is opened, so that the operation of the recorder is terminated. The control relay CR1 or CR2, as the case may be, is held picked up, however, over its stick circuit, but when relay TER picks up at the end of its slow pick-up interval to open its back contacts 29, 30 and 31, the stick circuit for the above mentioned control relay is opened with the result that such

control relay releases. The control relay being released, the circuit for relay TER is opened so that relay TER releases and the apparatus is restored to its normal condition.

Referring now to Fig. 3, the apparatus of Fig. 1 is modified in that the repeater relays RP1 and RP2, which are associated with relays R1 and R2, respectively, in the apparatus of Fig. 1, are eliminated. The pick-up circuit for relay R1 now passes from terminal B through track instrument M1, the winding of relay R1 and back contact 27 of relay CR2 to terminal C. The pick-up circuit for relay R2 now passes from terminal C through track instrument M2, the winding of relay R2 and back contact 28 of relay CR1 to terminal C. The stick circuit for relays R1 and R2; the pick-up and stick circuits for relays CR1 and CR2; the energizing circuits for relay SP, and the control circuit for device RD are all the same as were traced in detail for the apparatus of Fig. 1. The operation of the apparatus of Fig. 3 is similar to that described in detail for Fig. 1, as will readily be understood by reference to Fig. 3.

It is to be understood that while herein described, apparatus embodying my invention is employed to control a recording device, the scope of my invention embraces the control of any device which is desired to be controlled by actuators in a manner set forth hereinbefore.

Although I have herein shown and described only three forms of apparatus embodying my invention, it is to be understood that various changes and modifications may be made therein within the scope of the appended claims without departing from the spirit and scope of my invention.

Having thus described my invention, what I claim is:

1. In combination, a stretch of railway track, a first track instrument located at a first point along said stretch and a second track instrument located at a second point along said stretch and each being provided with a normally closed contact operable to an open position in response to a passing train, a first operating relay, an energizing circuit for said first operating relay including the contact of said first track instrument, a second operating relay, an energizing circuit for said second operating relay including the contact of said second track instrument, a slow pick-up relay, two energizing circuits for said slow pick-up relay each including a back contact of a different one of said first and second operating relays, a first control relay, a pick-up circuit for said first control relay including a back contact of said first operating relay and a back contact of said slow pick-up relay, a stick circuit for said first control relay including a front contact of said second operating relay, a second control relay, a pick-up circuit for said second control relay including a back contact of said second operating relay and a back contact of said slow pick-up relay, a stick circuit for said second control relay including a front contact of said first operating relay, an electroresponsive device, and control circuit means for controlling said device governed by front contacts of said first and second control relays.

2. In combination, a stretch of railway track, a first track instrument located at a first point along said stretch, a second track instrument located at a second point along said stretch, a first operating relay, an energizing circuit for said first operating relay governed by said first track

- instrument, a second operating relay, an energizing circuit for said second operating relay governed by said second track instrument, a slow pick-up relay, a first energizing circuit for said slow pick-up relay including a back contact of said first operating relay, a second energizing circuit for said slow pick-up relay including a back contact of said second operating relay, a first control relay, a pick-up circuit for said first control relay including a back contact of said first operating relay and a back contact of said slow pick-up relay, a stick circuit for said first control relay including a front contact of said second operating relay, a second control relay, a pick-up circuit for said second control relay including a back contact of said second operating relay and a back contact of said first operating relay, a third energizing circuit for said slow pick-up relay including a front contact of said second control relay, an electroresponsive device, and two control circuits for such device each including a front contact of a different one of said first and said second control relays.
3. Apparatus for recording the arrival of trains at selected points along a stretch of railway track comprising: a stretch of railway track, a first track instrument located at a first point along said stretch, a second track instrument located at a second point along said stretch, a first stick relay normally energized over a stick circuit governed by said first track instrument, a second stick relay normally energized over a stick circuit governed by said second track instrument, a slow pick-up relay, a first energizing circuit for said slow pick-up relay including a back contact of said first stick relay, a second energizing circuit for said slow pick-up relay including a back contact of said second stick relay, a first control relay, a pick-up circuit for said first control relay including a back contact of said first stick relay and a back contact of said slow pick-up relay, a stick circuit for said first control relay including a front contact of said second stick relay, a second control relay, a pick-up circuit for said second control relay including a back contact of said second stick relay and a back contact of said slow pick-up relay, a stick circuit for said second control relay including a front contact of said first stick relay, a pick-up circuit for said first stick relay governed by said first track instrument and including a back contact of said second control relay, a pick-up circuit for said second stick relay governed by said second track instrument and including a back contact of said first control relay, a normally deenergized recording device, and two energizing circuits for said device one of which is governed by a front contact of said first control relay and the other of which is governed by a front contact of said second control relay.
4. In combination, a stretch of railway track, a first track instrument located at a first point along said stretch, a second track instrument located at a second point along said stretch, a first operating relay governed by said first track instrument, a second operating relay governed by said second track instrument, a slow pick-up directional relay, a first energizing circuit for said directional relay governed by a back contact of said first operating relay, a second energizing circuit for said directional relay governed by a back contact of said second operating relay, a first control relay, a pick-up circuit for said first control relay including a back contact of said first operating relay and a back contact of said slow pick-up relay, a stick circuit for said first control relay including a front contact of said second operating relay, a second control relay, a pick-up circuit for said second control relay including a back contact of said second operating relay and a back contact of said first operating relay, a third energizing circuit for said slow pick-up relay including a front contact of said first operating relay, a fourth energizing circuit for said directional relay including a back contact of said second control relay, a time element relay governed by said first and second control relays, means governed by said time element relay for controlling the stick circuits for such control relays, an electroresponsive device, and two control circuits for such device each circuit being governed by a different one of said control relays.
5. In combination, a stretch of railway track, two track instruments located at spaced points along said stretch, an electroresponsive device, control means, energizing circuit governed by said control means for energizing said electroresponsive device, means governed by the track instrument first encountered by a train operating over said stretch in either direction for controlling said control means to establish the energizing circuit for said device, and other means governed by the other track instrument for controlling said control means to maintain the energizing circuit for said device until the train encounters said other track instrument.
6. In combination, a stretch of railway track provided with two track instruments located spaced apart along said stretch and each being provided with a normally closed contact operable to an open position in response to passing trains, a first operating relay, circuit means governed by the contact of a first of said two track instruments for energizing said first operating relay, a second operating relay, circuit means governed by the contact of the second of said two track instruments for energizing said second operating relay, two normally deenergized control relays, circuit means governed by said first operating relay and being effective when that relay is the first of said two operating relays to be released for momentarily energizing and picking up a first of said two control relays, stick circuit means for said first control relay governed by a front contact of said second operating relay, circuit means governed by said second operating relay and being effective when that relay is the first of said two operating relays to be released for momentarily energizing and picking up the second of said two control relays, stick circuit means for said second control relay governed by said first operating relay, an electroresponsive device, and two energizing circuits for said device each including a front contact of a different one of said two control relays.
7. In combination, a stretch of railway track provided with two track instruments located spaced apart along said stretch and each being provided with a normally closed contact operable to an open position in response to passing trains, a first operating relay normally energized over a stick circuit including the contact of a first of said two instruments, a first slow release repeater

relay controlled over a front contact of said first operating relay, a pick-up circuit for said first operating relay including the contact of said first track instrument and a back contact of said first repeater relay, a second operating relay normally energized over a stick circuit including the contact of the second of said two instruments, a second slow release repeater relay controlled over a front contact of said second operating relay, a pick-up circuit for said second operating relay including the contact of said second track instrument and a back contact of said second repeater relay, a slow acting directional relay, two energizing circuits for said directional relay each including a back contact of a different one of said operating relays, two control relays, circuit means including a back contact of said first operating relay and a back contact of said directional relay for picking up a first of said two control relays, stick circuit means for said first control relay including a front contact of said second operating relay and being effective to hold said first control relay picked up until said second operating relay is released, circuit means including a back contact of said second operating relay and a back contact of said directional relay for picking up the second of said two control relays, stick circuit means for said second control relay including a front contact of said first operating relay and being effective to hold said second control relay picked up until said first operating relay is released, an electroresponsive device, and two control circuits for such device one circuit including a front contact of said first control relay and the other circuit including a front contact of said second control relay.

8. In combination with a section of railway track provided with a track circuit including a track relay, two track instruments located at spaced points along said section and each being provided with a normally closed contact operable to an open position in response to passing trains, a first operating relay governed by the contact of a first of said two track instruments, a second operating relay governed by the contact of the second of said two track instruments, two normally deenergized control relays, an electroresponsive device, two energizing circuits for said device one circuit including a back contact of

said track relay and a front contact of a first of said control relays and the other circuit including a back contact of said track relay and a front contact of the second of said control relays, circuit means governed by said first operating relay and being effective when said first track instrument is the first of said two instruments to be encountered by a train operating over said section for momentarily energizing said first control relay to a picked-up position, stick circuit means for said first control relay governed by said second operating relay, circuit means governed by said second operating relay and being effective when said second track instrument is the first of said two track instruments to be encountered by a train operating over said section for momentarily energizing said second control relay to a picked-up position, stick circuit means for said second control relay governed by said first operating relay, a time element device controlled by said first and second control relays, and means governed by said time element device interposed in each said stick circuit means for removing said first and second operating relays from control of said stick circuit means for said second and first control relays respectively in the event that a train vacates said section after having encountered one of said two instruments but prior to encountering both said instruments.

9. The combination with a stretch of railway track provided with two track instruments located spaced apart along said stretch, a slow acting directional relay controlled by each of said two track instruments, an electroresponsive device provided with an energizing circuit, control relay means for controlling said energizing circuit, circuit means controlled by the one of said two track instruments first encountered by a train operating over said stretch in either direction and effective during the slow response period of said directional relay for controlling said control relay means to establish said energizing circuit, and other circuit means controlled by said control relay means and by the other of said two track instruments for controlling said control relay means to maintain established said energizing circuit until said train encounters said other track instrument.

HAROLD G. WITMER.
